UNITED STATES PATENT OFFICE.

FREDRIK OTTESEN, OF PITTSBURGH, PENNSYLVANIA.

SIGHT-FEED OILER.

1,172,039.

Specification of Letters Patent. Patented Feb. 15, 1916.

Application filed April 1, 1915. Serial No. 18,477.

To all whom it may concern:

Be it known that I, FREDRIK OTTESEN, a subject of the King of Norway, and resident of Pittsburgh, in the county of Allegheny and State of Pennsylvania, have invented certain new and useful Improvements in Sight-Feed Oilers, of which the following is a specification.

The transparencies through which the operation of sight feed oilers may be observed frequently become so clouded by vapor emanating from the oil as to seriously impair if not entirely obscure the view. This tendency is particularly marked in closed lubricating systems wherein the oil is repeatedly reused, sufficient water vapor and volatile constituents of the oil being frequently carried forward from the filter in sufficient amount to cause the above noted objectionable condition. I have found that this vapor deposit can be entirely avoided by having the sight feed chamber open to the atmosphere, and preferably in such manner as to cause the air to circulate therein.

Hence, one object of the present invention is to provide efficient means for admitting air to the sight feed chamber, together with means for shutting off the same when it is desired to feed the oil under pressure.

A further object is to improve the construction of the lubricator casing, and to provide for the removal and replacement of the sight feed glasses while the lubricator is in use.

In the accompanying drawings, Figure 1 is a front elevation, partly in section, of a sight feed oiler constructed in accordance with the invention. Fig. 2 is a vertical cross-section taken on line 2-2 of Fig. 1.

Referring to the drawings, the casing of the improved lubricator is formed with an oil-receiving chamber 2 and a delivering chamber 3, the arrangement being preferably such that these chambers are embodied in an integral structure. The oil feeds from chamber 2 through a nozzle 4 into the upper portion of chamber 3, and the drip or flow is controlled by needle valve 5 which is adjustable through stuffing box 6 on the upper side of chamber 2. In large power installations a number of sight feed oilers may be supplied from the same source, and to meet this condition opposite ends of chamber 2 are adapted to connect with the supply line 7, as shown. The bottom of chamber 3 may be provided with any suitable outlet fitting

or nozzle 8 for properly connecting the oiler with the part to be lubricated.

The opposite side walls of chamber 3 are of open cylindrical form as shown at 9, with each threaded internally and provided with the outwardly facing seat-forming shoulder 10. A piece of glass or other transparency 11 is fitted to each seat and is held in place by a gland 12, the flange-like outer edge of the latter being of angular form to receive a wrench. Washers 13 of suitable packing material at the inner and outer sides of the glass provide an effective seal.

The sight feed or delivering chamber 3 is suitably vented for the admission of atmospheric air, the presence of which forestalls the accumulation of sight-obstructing water and oil vapors on glasses 11. Venting for the accomplishment of this object may be variously embodied, although the arrangement is preferably such as to provide at least two vents at separated points to stimulate circulation. In the adaptation here shown, the closed rim-like wall 14 of chamber 3 is formed with the inwardly diverging ports 15 which ordinarily remain open and unobstructed and provide for the admission and circulation of air in amount sufficient to forestall vapor deposit and maintain the glasses transparent at all times. As it is desired under certain conditions to feed the oil under pressure, provision is had for closing ports 15 which in the present adaptation consists of the screw valve 16 which has its threaded stem adjustable in the threaded socket 17 located intermediate the air ports and with the valve head of sufficient area to close the ports for the pressure feed operation. By having the ports converge outwardly they are within reach of the single valve and at the same time their inner ends are sufficiently separated to sustain the desired circulation. For the normal operation, the valve simply remains open as in the adjustment shown in Fig. 1.

The advantages of the invention will be readily apparent to those skilled in the art. By maintaining the sight feed glasses constantly clear, much inconvenience is avoided, particularly where a number of oilers are under constant observation, any clogging tendency being instantly discernible. If the transparencies are broken they may be replaced without interfering with the operation, a facility not possessed by sight feed oilers now commonly in use, it being neces-

sary to shut off the oiler and take it apart to replace a broken glass. The chambered frame of the oiler is of simple and compact form, and may be readily applied to any 5 sight feed oiling system.

I claim:

1. A sight feed oiler having a visible passageway through which oil is adapted to flow, and means for affording a circulation 10 of air within the passageway, for the purpose described.

2. A sight feed oiler having a glass-in- 15 closed passageway closed to the atmosphere save for a plurality of vents for affording circulation of air through the passageway.

3. A sight feed oiler having a glass-in- 20 closed passageway closed to the atmosphere save for a plurality of vents for affording circulation of air therethrough for the purpose described, and vent closing means.

4. In a sight feed oiler, the combination 25 of a casing having receiving and delivering chambers in ported communication, a valve controlling such communication, the receiving chamber being provided with manifold connections whereby oil may pass through said chamber when communication with the delivering chamber is closed, the delivering chamber having a transparency through 30 which the flow of oil may be observed.

5. A sight feed oiler having a chamber 35 provided with a plurality of vents for affording circulation of air through the chamber, and a transparency for the chamber through which the flow of oil may be observed.

6. A sight feed oiler having a chamber 40 through which oil is fed from a source of supply, the chamber being vented for the admission of atmospheric air, valve means for controlling the passage of air, and a transparency for the chamber through which the flow of oil may be observed.

7. A sight feed oiler having a chamber 45 through which oil is fed from a source of supply, a wall of the chamber formed with a vent for the admission of atmospheric air,

a valve for closing the vent, and a transparency for the chamber through which the flow of oil may be observed.

8. A sight feed oiler having a chamber 50 through which oil is fed from a source of supply, a wall of the chamber formed with a vent for the admission of atmospheric air and an external screw-threaded socket, a 55 valve for closing said vent, the valve having a threaded stem adapted to enter the socket, and a transparency for the chamber through which the flow of oil may be observed.

9. A sight feed oiler having a chamber 60 through which oil is fed from a source of supply, a wall of the chamber formed with separated vents for the admission of atmospheric air to different portions of the chamber, a controlling valve common to the vents, 65 and a transparency for the chamber through which the flow of oil may be observed.

10. A sight feed oiler having a chamber 70 through which oil is fed from a source of supply, a wall of the chamber formed with two separated vents for the admission of atmospheric air and with an external screw-threaded socket located between the vents, a valve common to the two vents, the valve having a threaded stem adapted to enter 75 said socket, and a transparency for the chamber through which the flow of oil may be observed.

11. In a sight feed oiler, the combination 80 of a casing having receiving and delivering chambers in ported communication, a valve controlling such communication, the delivering chamber having sight openings in opposite walls thereof with transparencies closing said openings, and means for affording 85 a circulation of air through the delivering chamber.

In testimony whereof I affix my signature in presence of two witnesses.

FREDRIK OTTESEN.
